CLAIM

The ornamental design for an expandable cable harness storage, as shown and described.

DESCRIPTION

FIG. 1 is a front perspective view of an expandable cable harness storage, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of the design shown in use; and,

FIG. 10 is a perspective view of the design shown in an alternate configuration.

The broken lines in the drawings illustrate the portions of the expandable cable harness storage, which form no part of the claimed design.
